UNITED STATES PATENT OFFICE.

JACK W. JAMES, OF CUBA, TENNESSEE.

BATHING-MACHINE.

SPECIFICATION forming part of Letters Patent No. 366,110, dated July 5, 1887.

Application filed December 28, 1886. Serial No. 222,828. (No model.)

To all whom it may concern:

Be it known that I, JACK W. JAMES, a citizen of the United States, residing at Cuba, in the county of Shelby and State of Tennessee, 5 have invented new and useful Improvements in Bathing-Machines, of which the following is a specification.

This invention relates to improvements in the bathing-machines for which Letters Patent to Nos. 350,489 and 350,490 were granted to me October 12, 1886; and the present invention consists in the combination, with a bathing-machine frame constructed as described, of a bathing-chamber in portable water-proof casting supported above the machine-platform to provide an inclosed space for the bather; air purifying, drying, heating, and medicating devices located beneath or near said platform and communicating with the inclosed space 20 above; a pair of rotary brushes journaled in a swinging frame supported in the upper part of the machine-frame to apply friction to the bather's head, and an adjustable rotary towel-shaft arranged and operating as hereinafter 25 described, and carrying a detachable towel to deliver a succession of blows on the bather's body, the object of the invention being to provide for family use an improved form of Turkish bathing at a very low cost.

30 In the accompanying drawings, Figure 1 is a perspective view of a bathing-machine embodying my invention. Fig. 2 is a front view of the head-rubbing attachment. Fig. 3 is a rear view of the lower part of the machine, 35 showing the devices for purifying, drying, heating, and medicating the air employed in the bath. Fig. 4 is a detail view of the mechanism for supporting and operating the adjustable rotary towel-shaft.

40 The numeral 1 designates a platform having front supports, 2, and supported at the rear by uprights 3, that are connected with the supports 2 by horizontal braces in any suitable manner. The uprights 3 are preferably 45 connected at the top by a cross-piece or arch, 4, which may be provided with a hook, 5, from which to suspend a showering or douche device, as shown in my above-named Patent No. 350,489.

50 To the upper part of each upright 3 is attached an arm, 6, for supporting and bracing a horizontal frame, 7, which is preferably cir-

cular in form and made of metal. Over this circular horizontal frame 7 is thrown a flexible water-proof casing, 8, made of canvas, oil-cloth, or other suitable material. By means of this removable or detachable water-proof casing which envelops the machine an inclosed space for the bather is provided above the machine-platform. The water-proof casing 8 is provided at suitable points with transparent panels 9, to admit light to the interior, and it also has an opening controlled by a slide, 10, for regulating the temperature by permitting the free escape of heated air, as herein-after described. In one side of the casing is a longitudinal slit, 12, through which the bather can pass, and this slit or opening can be closed by buckles 13, as shown, or other suitable fastenings.

7c Between the uprights 3, near the top, is journaled a shaft, 14, carrying a pulley, 15, driven from a large pulley, 16, on a driving-shaft, 17, beneath or near the bather's platform. On the shaft 14 is loosely mounted a 75 swinging frame, 18, held from lateral movement by set-collars 19 at each side. Secured to the shaft 14 within the swinging frame 18 is a concaved roller-brush, 20, and on a shaft, 21, journaled in the front or lower part of said 80 frame, is secured a similar concaved roller-brush, 22, the two brushes being driven together by means of belting 23 between pulleys 24 and 25 on their respective shafts. The brushes 20 and 22 are actuated through belting 26, connecting the pulleys 15 and 16, as shown. To the upper or rear part of the 85 swinging frame 18 is secured a counterpoise, 27, and to the front of the said frame is attached a cord, 28, by grasping which the bather 90 can draw the forward part of the frame 18 down and so bring the concaved rotary brushes 20 and 22 into contact with his head. On the driving-shaft 17 is a crank-wheel, 29, by which 95 said shaft is actuated. The driving-shaft 17 also supports a loosely-mounted arm, 30, which projects in a forward and upward direction, 100 and has pivoted to its forward end a backward and upward projecting bar, 31, in the rear end of which a rotary towel-shaft, 32, is journaled. At the junction of the arm 30 and bar 31 is a pulley, 33, and on the towel-shaft 32 another pulley, 34, is secured. The pivoted bar 31 is provided with a longitudinal slot, 35, in

which is arranged a sliding block, 36, having bearings for a pulley, 37, and within the slot 35 is also placed a spring, 38, one end of which bears against said block. The crank-wheel 29 and pulleys 33, 34, and 37 are each grooved to receive a connecting-belt, 39, through which the towel-shaft 32 is rotated, the arrangement of the several parts being such that the spring-pressed block 36 and attached pulley 37 will 10 serve to automatically regulate the tension of the belt 39 according to the position of the adjustable arm 30 and bar 31, said arm and bar being raised and lowered, as required, by means of a cord, 40, which is attached to the 15 rear end of the bar 31, then passed over a pulley, 41, on the upper part of the machine-frame, and provided at its lower end with a weight, 42, by which the arm 30 and bar 31 are counterbalanced and supported at any desired height. It is obvious that by grasping 20 the cord 40 and through it raising or lowering the arm 30, bar 31, and shaft 32 the bather can readily bring into contact with any part of his body the rotating towel 43, which is detachably secured to the rotary shaft 32.

Beneath or near the machine-platform, but preferably in rear thereof, as shown, is placed a box or receptacle, 44, for holding charcoal or other absorbent material. This receptacle 30 is provided with a removable cover and has air-inlets 45 at one end. At its other end the receptacle 44 communicates through a tube, 46, with the interior of a fan or air-pump casing, 47. In this casing is an air-pumping device that is driven by belting 48 from the driving-shaft 17 through pulleys 49 and 50.

The casing 47 has an exit-pipe, 51, which communicates with a receptacle, 52, for absorbent material capable of drying the air. 40 The pipe 51 is then extended in coiled form above a lamp, 53, that communicates with a receptacle, 54, containing any medicinal substance or perfume, and finally terminates in branches 55, that pass through the platform 1, 45 to discharge the purified, dried, heated, and medicated air into the inclosed space above the machine-platform.

The manner of using this bathing apparatus will be readily understood from the foregoing 50 description. If desired, the head-rubbing attachment can be readily detached by disconnecting from the uprights 3 the removable bearings 56, in which the shaft 14 is journaled.

The adjustable rotary towel-shaft 32 and its supports can also be readily detached from the 55 machine-frame. The receptacles 44, 52, and 54 are each provided with removable lids to facilitate renewal of their contents when required, and, if desired, the air heating and medicating devices can be used either with or 60 without the friction appliances. The driving-shaft 17 can also be arranged to actuate other attachments or accompaniments of a bathing-machine, (not here shown,) but which have 65 been described in my former patents, above mentioned.

With the detachable water-proof casing or bathing-chamber 8, rotary head-brushes 20 and 22, and the air heating and medicating devices here described, the value of the machine is 70 greatly increased by reason of the more extended and varied uses to which it can be applied.

What I claim as my invention is—

1. In a bathing-machine, the combination, 75 with the machine frame and platform, of a swinging counterbalanced frame journaled in the upper part of the machine, a pair of rotary concaved brushes arranged in said swinging frame, and means for actuating said brushes 80 and swinging frame to apply friction to the bather's head, substantially as described.

2. In a bathing-machine, the combination, 85 with the machine frame and platform and a driving-shaft and pulley, of an arm loosely mounted on said shaft, a bar pivoted to said arm and carrying a belt-tightener and pulley, a rotary towel-shaft journaled in said bar and provided with a pulley, and a counter-balance for said arm and bar, substantially as described. 90

3. A bathing-machine comprising the platform 1, bathing chamber or casing 8, supported above said platform, counterpoised swinging frame 18, rotary brushes 20 and 22, adjustable rotary towel-shaft 32, air-purifying and air- 95 medicating receptacles 44, 52, and 54, air-pump 47, lamp 53, and a tube, 51, connecting said receptacles and pump with the spaces within the bathing chamber or casing, substantially as described.

In testimony whereof I affix my signature in presence of two witnesses.

JACK W. JAMES.
